ATTORNEY

UNITED STATES PATENT OFFICE

EDWIN A. PARKER, OF BALTIMORE, MARYLAND

PROCESS OF AND MEANS FOR DECORATING ROLLED METAL

Application filed May 8, 1929. Serial No. 361,512.

This invention relates to a process of and means for the treatment of rolled tin or other metal in the application to such metal of designs, decorations and other indicia, the general object of the invention being to provide means for the preliminary treatment of the metal, such as the cleaning and coating thereof, means for applying the indicia to the metal and the finishing of the decorated metal, such as by means of varnish or the like, with drying means for drying the material placed on the tin after each application of such material, with means whereby the metal is passed through all of the before mentioned means in a continuous manner.

Another object of the invention is to provide means for forming portions of the metal into desired articles as it passes from the last drying means, with a roll around which the skeleton or scrap metal is wound after it leaves the forming means.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing which shows a diagrammatic sectional view of one manner of carrying out the invention.

As is known to the trade, metal, such as tin, is obtainable in rolls, such as shown at 1, and in carrying out my invention, I provide supporting means 2 for rotatably supporting the roll and immediately adjacent the supporting means, I provide a housing 3 or other support for the cleaning rolls 4, the guiding rolls 5 being arranged at the sides of the housing for guiding the metal into and from the housing. From the housing 3, the metal passes to a coater device 6 which applies a coating to the metal and from this coater, the metal passes to an oven 7 which is divided into two vertical chambers by a partition 8. Magnetic rolls 9 are arranged in the oven, which contact the rear face of the metal and cause the metal to pass upwardly through the first chamber and then downwardly through

the second chamber. I prefer to arrange the heating medium in the first chamber so that the metal is dried in this chamber and is cooled as it passes through the rear chamber. The metal then passes into a printing press 55 10 which is of any desired construction and from this press, the metal passes into a second oven 11 which is of the same construction as the first oven. If desired, the metal can be passed through other presses and an oven 60 must be provided for each press so as to dry the material placed on the metal by the press before the metal passes to another press. From the last oven, the metal passes into a varnisher 12 and from this varnisher, the 65 metal passes into a third oven 13. The metal from this oven 13 passes to a die press 14 which forms the articles and then the scrap or skeleton metal passes to the roll 15 upon which it is wound, this roll being rotatably 70 supported by the uprights 16. The articles formed in the die press may be passed to the threader 17, if desired.

From the foregoing it will be seen that the metal is treated in a continuous manner during the process of cleaning and preparing it for the application of the designs or other indicia and the applications of such indicia, as well as the formation of the articles. By 75 rolling the skeleton metal on a roll, the scrap material can be easily and quickly handled as it is not deposited on the floor around the press. It will, of course, be understood that the invention can be used in applying various kinds of material to the metal, such as the application of lacquers, varnishes, dusting materials, etc., and that the metal can have the indicia applied thereto in various ways, such as lithographing, printing, etc. The printing plates may be either made in relief, intaglio or surface and either direct or offset process can be used. The metal may be coated by rolls or sprayer and either single or multi-color presses can be used in series or single.

With this invention, various kinds of articles, such as caps, boxes, cans, etc., are formed from a roll of metal without handling sheets of metal as is now done. The machine will require the services of but a few men and by 100

using the rolls, much labor will be saved in opening the boxes which contain the sheet metal.

It is thought from the foregoing description that the advantages and novel features of the invention will be readily apparent.

It is to be understood that changes may be made in the construction and in the combination and arrangement of the several parts, 10 provided that such changes fall within the scope of the appended claims.

What I claim is:—

1. An apparatus of the class described comprising a support for rotatably supporting a roll of metal, a cleaner arranged adjacent the support and through which the metal passes, a coater for coating the metal after it passes from the cleaner, a drying device for receiving metal from the coater, a device 15 for applying indicia to the metal after it leaves the drying device, a drying device for receiving the metal from the indicia applying device, a device for applying a finishing coat to the metal after it leaves the last drying device, a drying device for receiving the metal from the coating device and a press for forming articles from the indicia carrying portions of the metal and means whereby the metal is caused to pass through the various 20 devices in a continuous manner.

2. An apparatus of the class described comprising a support for rotatably supporting a roll of metal, a cleaner arranged adjacent the support and through which the metal passes, a coater for coating the metal after it passes from the cleaner, a drying device for receiving metal from the coater, a device for applying indicia to the metal after it leaves the drying device, a drying device 25 for receiving the metal from the indicia applying device, a device for applying a finishing coat to the metal after it leaves the last drying device, a drying device for receiving the metal from the coating device, a cutting device receiving the metal from the last drying device and means whereby the metal is caused to pass through the various devices in a continuous manner and a rotatably supported roll for receiving the 30 skeleton metal from the press.

3. An apparatus of the class described comprising a support for rotatably supporting a roll of metal, a cleaner arranged adjacent the support and through which the metal 35 passes, a coater for coating the metal after it passes from the cleaner, a drying device for receiving metal from the coater, a device for applying indicia to the metal after it leaves the drying device, a drying device for receiving the metal from the indicia applying device, a device for applying a finishing coat to the metal after it leaves the last drying device, a drying device for receiving the metal from the coating device and a press for forming 40 articles from the indicia carrying portions of the metal and means whereby the metal is caused to pass through the various devices in a continuous manner.

tions of the metal and means whereby the metal is caused to pass through the various devices in a continuous manner, each drying device including magnetic rolls for guiding the metal therethrough.

4. An apparatus of the class described comprising a support for rotatably supporting a roll of metal, a cleaner arranged adjacent the support and through which the metal passes, a coater for coating the metal after it passes from the cleaner, a drying device for receiving the metal from the coater, a device for applying indicia to the metal after it leaves the drying device, a drying device for receiving the metal from the indicia applying device, a device for applying a finishing coat to the metal after it leaves the last drying device, a drying device for receiving the metal from the coating device and means whereby the metal is caused to pass through the various devices in a continuous manner.

5. An apparatus of the class described comprising a support for rotatably supporting a roll of metal, a cleaner arranged adjacent the support and through which the metal passes, a coater for coating the metal after it passes from the cleaner, a drying device for receiving the metal from the coater, a device for applying indicia to the metal after it leaves the drying device, a drying device for receiving the metal from the indicia applying device, a device for applying a finishing coat to the metal after it leaves the last drying device, a drying device for receiving the metal from the coating device, a cutting device receiving the metal from the last drying device and means whereby the metal is caused to pass through the various devices in a continuous manner.

6. A herein-described method of manufacture for making a plurality of articles from a strip of rolled metal, said metal first cleaned as it is unrolled, then coated, then dried, then printed with indicia, then dried and varnished to retain the printed indicia and coating thereon, then dried, then portions of the metal formed into desired articles and the unused metal wound on a drum.

In testimony whereof I affix my signature.

EDWIN A. PARKER.
